[57] **CLAIM**

The ornamental design for an embossed tissue, as shown and described.

DESCRIPTION

FIG. 1 is a top plan view of an embossed tissue showing our new design. The embossed tissue is shown cut away on each of its four sides to indicate indeterminate length and width. The broken lines form no part of the claimed design and depict one repeat unit of the design, which repeats uniformly throughout the entire surface of the tissue. The bottom plan view forms no part of the claimed design; and.

FIG. 2 is an enlarged fragmentary cross-sectional view along line 2—2 as shown in FIG. 1.
